(57) **ABSTRACT**

A new *Osteospermum* plant particularly distinguished by having a violet ray floret color, medium flower size, and compact and mounding plant habit, is disclosed.

1 Drawing Sheet

1

Genus and species: *Osteospermum hybrida*.
Variety denomination: 'SAKOST8076'.

BACKGROUND OF THE NEW PLANT

The present invention comprises a new and distinct cultivar of *Osteospermum*, botanically known as *Osteospermum hybrida*, and hereinafter referred to by the cultivar name 'SAKOST8076'. 'SAKOST8076' originated from a hybridization of proprietary hybrid *Osteospermum* commercial lines 'Akkalav' and 'Sun-sation Blue' in Aabyhoej, Denmark. The female parent, 'Akkalav' has a lavender with blue eye flower color and a compact plant habit. The male parent, 'Sun-sation Blue', has a purple flower color and a mounding plant habit.

In May 2004, the two *Osteospermum* lines were crossed and seeds were obtained. The seeds were sown and 200 F₁ plants were grown in pots for evaluation. A single plant having medium-sized blue-colored flowers and a compact and mounding plant habit was selected for further evaluation and propagation.

In February 2005, the single plant was vegetatively propagated by cuttings and re-evaluated in an open field and a greenhouse, and assigned the breeder code number '205114'.

In spring 2005, '205114' plants were evaluated again in pots and in an open field. '205114' was named 'SAKOST8076' and was found to reproduce true to type in successive generations of asexual propagation through vegetative cuttings.

SUMMARY OF THE INVENTION

The following are the most outstanding and distinguishing characteristics of this new cultivar when grown under normal horticultural practices in Salinas, Calif.

2

1. Antique blue or violet ray floret color;
2. Medium flower size; and
3. Compact and mounding plant habit.

5 **DESCRIPTION OF PHOTOGRAPHS**

This new *Osteospermum* plant is illustrated by the accompanying photographs which show the plant's overall plant habit including form, foliage, and flowers. The photographs 10 are of a plant grown six months from transplant date and ten months from stick date into 8-inch pots from rooted cuttings in Salinas, Calif. in the spring of 2009 through the winter of 2010. The colors shown are as true as can be reasonably obtained by conventional photographic procedures.

15 FIG. 1 shows overall plant habit of the plant grown in a pot.
FIG. 2 shows the mature inflorescence of the plant.

DESCRIPTION OF THE NEW CULTIVAR

20 The following detailed descriptions set forth the distinctive characteristics of 'SAKOST8076'. The data which define these characteristics were collected from asexual reproductions carried out in Salinas, Calif. Data was collected on plants grown approximately six months from transplant date and ten months from stick date into 8-inch pots under greenhouse conditions in Salinas, Calif. in the spring of 2009 through the winter of 2010. Color references are to The R.H.S. Colour Chart of The Royal Horticultural Society of London (R.H.S.), 4th edition.

25 **DESCRIPTION OF THE NEW PLANT**

Classification:

Family.—Compositae.

Botanical.—*Osteospermum hybrida*.

Common.— <i>Osteospermum</i> , Cape Daisy, South African Daisy.	Base.—Attenuate.
Designation.—‘SAKOST8076’.	Margin.—Serrate.
Parentage:	Venation.—Pinnate.
Female parent.—A hybrid proprietary <i>Osteospermum</i> line ‘Akkalav’ (unpatented).	Surface (both surfaces).—Dull.
Male parent.—A hybrid proprietary <i>Osteospermum</i> line ‘Sun-sation Blue’ (unpatented).	Surface pubescence (both surfaces).—Very slight, mainly around edge.
Growth:	Pubescence color (both surfaces).—RHS N155A (White).
Time to produce a rooted cutting.—Cuttings will colonize a 2.5 cm diameter by 2.5 cm tall greenhouse tray cell with peat-based plant media in approximately four weeks. Cuttings are dipped in a normal dilution (1:9) of DIP 'N GROW root inducing solution in water. The trays are misted hourly during rooting.	Attachment.—Decurrent.
Environmental conditions for plant growth.—Rooted cuttings are transplanted to pots with a 16 cm diameter, one plant per pot. Peat-based growing media is used. The pots are watered using a 150 ppm to 200 ppm fertilizer solution using 18-8-18 fertilizer. The soil is allowed to dry between watering. During the first few weeks after transplanting, the plants should have evening temperatures around 15° C. to 18° C. for good root growth. When plants reach 7.5 cm to 10 cm in height, they are pinched back to 5 to 6 leaves to promote branching. Spring and summer daytime high temperatures in Salinas, Calif., where the data was collected, range from 16° C. to 25° C.	Length.—7.0 cm.
Time to bloom from propagation.—Approximately four weeks when rooted vegetative cuttings are transferred to a 5-inch diameter pot. Flowering season is all year in the United States. Vernalization is not required to induce flowering.	Width.—3.0 cm.
Plant description:	Thickness.—Less than 0.1 cm.
Habit.—Compact and mounding.	Color.—Upper surface: RHS 137A (Green). Lower surface: RHS 137B (Green).
Life cycle.—Perennial.	Venation color.—Upper surface: RHS 144A (Yellow-green). Lower surface: RHS 144B (Yellow-green).
Form.—Compact, mounding.	Inflorescence:
Height (from soil line to first node).—2.0 cm.	Number per plant.—20.
Height (from soil line to top of foliage).—24.0 cm to 26.0 cm.	Type.—Capitulum (head); disc florets are perfect and ray florets are carpellate.
Width.—50.0 cm to 52.0 cm.	Flowering habit.—Determinate.
Stems:	Lastingness of flowers.—3 to 4 days.
General.—Multiple stems, circular in cross section.	Fragrance.—Absent.
Stem length (total).—12.0 cm to 14.0 cm.	Seed production.—None observed.
Diameter.—0.2 cm.	Diameter.—7.0 cm.
Internode length.—2.0 cm.	Depth.—1.0 cm.
Color.—RHS 143C (Green).	Petal (ray floret) number.—20 to 26 per inflorescence.
Pubescence.—Moderate. Color: RHS N155A (White).	Disc diameter.—1.2 cm.
Shape: Short, hair-like fibers.	Disc floret number.—50 to 60 per inflorescence.
Branches:	Peduncle length.—5.0 cm from inflorescence to first node.
General.—Circular in cross section.	Peduncle diameter.—0.2 cm.
Number of main branches.—1.	Peduncle color.—RHS 143B (Green).
Total number of branches.—12.	Peduncle texture.—Dull, slight pubescence.
Length.—12.0 cm to 14.0 cm, approximately 2.0 cm from soil line to first node, 2.0 cm between first and second nodes.	Phyllaries.—Arrangement: 20 per inflorescence, free, arranged symmetrically. Length: 1.2 cm. Width: 0.1 cm. Apex: Acute. Margin: Entire. Shape: Linear, acute. Color: Upper surface: RHS 143A (Green). Lower surface: RHS 143B (Green).
Diameter.—0.5 cm.	Ray florets (ligules):
Internode length.—2.0 cm.	Corolla.—One petal per ray floret; only the outer row of florets are the ray florets.
Color.—RHS 143B (Green).	Number of ray florets.—22 to 26 per inflorescence.
Pubescence.—Moderate. Color: RHS N155A (White).	Length.—3.0 cm.
Shape: Short, hair-like fibers.	Width.—0.7 cm.
Leaves:	Shape.—Lanceolate.
Arrangement.—Alternate.	Apex.—Acute.
Shape.—Oblanceolate.	Margin.—Entire.
Apex.—Acute.	Color.—Upper surface: RHS N87C. Lower surface: RHS N87D.
	Pubescence.—Glabrous.
	Disc florets:
	Color.—RHS 77A (Purple).
	Shape.—Tubular.
	Apex.—Pointed.
	Surface.—Dull, pubescent.
	Size.—Length: 0.4 cm. Width: 0.1 cm.
	Reproductive organs:
	Ovary.—Superior in ray florets.
	Pistil form.—One style with two stigma branches in ray florets.
	Pistil length.—0.5 cm in ray florets.
	Stigma color.—RHS 187A (Greyed-purple) in ray florets.
	Style color.—RHS 155A (White) in ray florets.

Ovary.—Superior in disc florets.

Pistilform.—One style with two stigma branches in disc florets.

Stamens.—5, fused into a single tube in disc florets.

Anther color.—RHS 187A (Greyed-purple) in disc florets.

Pollen color.—RHS 17A (Yellow-orange) in disc florets.

Filament color.—RHS 155A (White) in disc florets.

Disease and insect resistance: Plants are susceptible to aphids, thrips, whiteflies, and worms.

COMPARISON WITH PARENTAL LINES AND KNOWN CULTIVARS

‘SAKOST8076’ is a distinct variety of *Osteospermum* owing to its violet ray floret color, medium flower size, and compact and mounding plant habit. ‘SAKOST8076’ is distinguished from its parents as described in Table 1 (color references are to The Royal Horticultural Society Colour Chart, 4th edition):

TABLE 1

Comparison with Parental Lines			
Characteristic	Male Parent ‘SAKOST8076’	Female Parent ‘Sun-sation Blue’	Female Parent ‘Akkalav’
Ray floret (ligule) color, upper surface	RHS N87C	Purple	Lavender with blue eye

TABLE 1-continued

Comparison with Parental Lines			
Characteristic	Male Parent ‘SAKOST8076’	Female Parent ‘Sun-sation Blue’	Female Parent ‘Akkalav’
Plant growth habit	Compact and mounding	Mounding	Compact

‘SAKOST8076’ is a distinct variety of *Osteospermum* owing to its violet ray floret color, medium flower size, and compact and mounding plant habit. ‘SAKOST8076’ is most similar to the *Osteospermum* plant named ‘Malindi’ (U.S. Plant Pat. No. 13,343). Differences between the two varieties are described in Table 2 (color references are to The Royal Horticultural Society Colour Chart, 4th edition):

TABLE 2

Comparison with Similar Variety		
Characteristic	‘SAKOST8076’	‘Malindi’
Ray floret (ligule) color, upper surface	RHS N87C	RHS N78A
Plant growth habit	Compact and mounding	Upright habit

I claim:

1. A new and distinct cultivar of *Osteospermum* plant as shown and described herein.
